UNITED STATES PATENT OFFICE.

JOHN HARTFORD CHIDESTER, OF SUMMIT, NEW JERSEY.

ILLUMINATED DISPLAYING DEVICE.

1,344,379.

Specification of Letters Patent.

Patented June 22, 1920.

Application filed March 1, 1917. Serial No. 151,651.

To all whom it may concern:

Be it known that I, JOHN HARTFORD CHIDESTER, a citizen of the United States, and a resident of Summit, in the county of 5 Union and State of New Jersey, have invented certain new and useful Improvements in Illuminated Displaying Devices, of which the following is a specification.

The invention relates to a device to be 10 used in connection with a "stock ticker" or like machines, and is designed to render the tape simultaneously visible to a large number of persons, and this without handling the tape by individuals and to discharge the 15 tape so that it may be inspected in the usual way if desired.

Objects and advantages of the invention will be set forth in part hereinafter, and in 20 part will be obvious herefrom, the same being realized and attained through the instrumentalities and combinations set forth in the appended claim.

The invention consists in the novel parts, 25 constructions, arrangements, combinations and improvements herein shown and described.

The accompanying drawings, referred to herein, and forming a part hereof, illustrate 30 one embodiment of the invention, the same serving in connection with the description to explain the principles of the invention.

Of the drawings:—

Figure 1 is a side elevation of a device 35 constructed in accordance with the principles of the invention, shown attached to the usual form of stock ticker;

Fig. 2 is a vertical, transverse section on the line A—B of Fig. 1, looking in the direction of the arrows;

Fig. 3 is a horizontal, fragmentary section on the line C—D of Fig. 1, looking in the direction of the arrows;

Fig. 4 is a fragmentary, sectional detail of a magnifying device; and

Fig. 5 is a similar view of a reflecting and magnifying device.

Referring to the accompanying drawings, illustrating by way of example one embodiment of the invention, portions of a stock 50 ticker are shown, comprising a substantially circular frame 1, supporting a bracket 2 for the paper roll 3, the web 4 of paper passing from the roll through the machine and being imprinted in a well-known manner.

Various parts of the stock ticker are shown 55 in dotted lines including the rolls 5, 6, 7 and 8 which feed the strip through the machine.

The machine of my present invention is provided with an annular frame 10, fitting over the frame 1 of the stock ticker, and 60 being attached thereto in a suitable manner, as by clamping screws 11 and 12. Supported upon the frame 10 and upon the bracket 13 extending outwardly therefrom is a casing 14. Within the casing are provided 65 means for illuminating the printed ticker strip 4 and for projecting and displaying the strip so that it may be simultaneously viewed by a large number of persons at a relatively great distance. Referring more 70 to the embodied exemplification, a supporting runway 16 is provided, extending horizontally. At the forward end of the runway 16 are upwardly extending lugs 17 and 18, which serve as side guides for the 75 tape, and which support a guiding roller 19, located above the tape 4. At the other end of the runway 16, are lugs 20 generally similar to lugs 17 and 18, and a top guiding and holding roller 21 similar to the roller 19. 80

Means are provided for feeding the tape through the device as it is printed and supplied from the ticker, said means being adapted to keep the tape smooth and flat upon the runway 16. The embodied form 85 of such means comprises a clock mechanism 22, which mechanism drives a gear 23, the gear 23 meshing with a gear 24 upon the shaft of a roller 25, located beneath the tape 4. Coöoperating with the driven feeding 90 roller 25 is a spring pressed roller 26 engaging with the upper face of the tape, and being resiliently pressed downward by a spring or springs 27, the two rollers thus providing a friction or slip feed and tension upon the 95 tape 4. A guiding lip or plate 28 may be utilized to facilitate the threading of the strip 4 through the machine.

In the embodied form of illuminating means, a lamp 35 is mounted within the casing 14, and extends along in the same direction as the tape 4. The lamp 35 is provided with a reflector 36, adapted to reflect the light from the lamp upon the ticker strip 4. The light is thence reflected by means 100 of mirrors, utilizing also, if desired, a magnifying device, and is finally presented at 105 the exhibition point to be viewed, as al-

ready stated, by a relatively large number of persons simultaneously and at relatively a great distance from the device.

In the embodied form, a magnifying device is utilized comprising a bar of glass 37, mounted in a frame 38, which frame is carried by brackets 39 and 40 at either end of the casing. The brackets are supported, respectively, by bolts 41, with which they have a slotted connection, as shown clearly in Fig. 2, thereby affording both transverse and angular adjustment for the magnifying device 37.

The light from the ticker strip 4, whether the magnifying device be utilized or omitted, is received upon a mirror 43, which mirror is supported in a frame 44, the frame being supported in brackets 45 and 46, which brackets, respectively, are attached to the casing 14 by bolts 47. The mirror 43 is thus capable of angular adjustment as desired. From the mirror 43 the image from the ticker tape is reflected to a mirror 48, which mirror is supported in a frame 49, carried by brackets or lugs 50 and 51. These brackets are supported, respectively, upon the casing 14 by bolts 52, thereby being likewise capable of angular adjustment.

The casing 14 is provided with convenient doors or closures, a door 54 having a plate of glass or other transparent material 55 therein, which permits viewing of the printing on the ticker tape at the exhibition point, as already described, and provides access to the upper part of the casing 14. A transparent slide 56 permits a direct view of the ticker tape 4 upon the runway 16, where it is strongly lighted by the lamp 35. A door 57 permits access to the ticker mechanism.

It will be seen that the device, while possessing the advantages pointed out, is attachable to an ordinary ticker without

changing any of the mechanism thereof, merely by the use of the clamping screws 11 and 12.

45

Fig. 4 represents a form of double convex magnifying bar 37 and Fig. 5 represents a form of magnifying mirror.

From all the foregoing it will be understood that a device has been provided embodying the objects and advantages herein set forth, together with other objects and advantages, which will be obvious or which may be ascertained from practice with the invention. It will also be understood that changes may be made from the structure shown and described, within the scope of the accompanying claim, without departing from the principles of the invention and without sacrificing its chief advantages.

55

What I claim as my invention and desire to secure by Letters Patent is:—

60

An attachment for stock tickers comprising in combination a frame having a contour to conform to the shape of a stock ticker cabinet, means for removably securing said frame to said cabinet, a casing fixed to frame and having communication with the ticker tape outlet of said cabinet, said casing being provided with a pair of sight openings, means to feed a ticker tape from said outlet transversely of said casing and in visible relation to one of said sight openings, a lamp arranged to illuminate said tape, transparent material in said openings, and means to project upon the other of said openings a true image of tape data.

65

In testimony whereof, I have signed my name to this specification, in the presence of two subscribing witnesses.

JOHN HARTFORD CHIDESTER.
